(57) **CLAIM**

The ornamental design for a shoe outsole periphery and bottom, as shown and described.

DESCRIPTION

FIG. 1 is a perspective view of a shoe outsole periphery and bottom in accordance with my new design.

FIG. 2 is a left side view thereof;

FIG. 3 is a right side view thereof;

FIG. 4 is a top plan view thereof;

FIG. 5 is a bottom plan view thereof;

FIG. 6 is a rear elevation view thereof; and,

FIG. 7 is a front elevation view thereof.

The broken lines showing the remainder of the shoe represent unclaimed subject matter only and form no part of the claimed invention.
